(57) **CLAIM**

The ornamental design for a module cabin of an agricultural harvesting tractor, as shown and described.

DESCRIPTION

The patent or application file contains at least one drawing executed in color. Copies of this patent or patent application publication with color drawing(s) will be provided by the Office upon request and payment of the necessary fee.

1. Module cabin of an agricultural harvesting tractor
Figure 1.1 is a front left perspective view of the module cabin.

Figure 1.2 is a right view of the module cabin.

Figure 1.3 is a front view of the module cabin.

Figure 1.4 is a rear view of the module cabin.

Figure 1.5 is a top left perspective view of the module cabin.

Figure 1.6 is a top view of the module cabin.

Figure 1.7 is a bottom view of the module cabin.

Figure 1.8 is a left view of the module cabin.

The design shows a module cabin of an agricultural harvesting tractor.
